UNITED STATES PATENT OFFICE.

HENRY PAAR, OF CANTON, OHIO, ASSIGNOR TO JOHN L. ARNOLD,
OF SAME PLACE.

DESIGN FOR A HORSESHOE-PAD.

SPECIFICATION forming part of Design No. 32,204, dated February 6, 1900.

Application filed December 30, 1899. Serial No. 742,157. Term of patent 14 years.

To all whom it may concern:

Be it known that I, HENRY PAAR, a citizen of the United States, residing at Canton, in the county of Stark and State of Ohio, have 5 invented and produced a new and original Design for a Horseshoe-Pad, of which the following is a specification, reference being had to the accompanying drawings, forming a part thereof.

10 Figure 1 is a bottom view of a horseshoe-pad, showing my new design; and Fig. 2 is a rear elevation of the same.

As shown in the drawings, the leading or material features of my design consist of a 15 substantially horseshoe-shaped body A, having broadened rounded ends *a*, an external flange projecting outward from the upper edge of said body, which flange, near the rear

ends of the body, is gradually narrowed and extends as a very narrow flange around the 20 rounded ends, and a groove C in the outer periphery of the body just below the flange, which groove also extends around the rounded ends of the body.

Having described my invention, what I 25 claim as new, and desire to secure by Letters Patent, is—

The design for a horseshoe-pad as herein shown and described.

In testimony whereof I hereunto affix my 30 signature in the presence of two witnesses.

HENRY PAAR.

Witnesses:

J. A. JEFFERS,
J. R. BOND.
